UNITED STATES PATENT OFFICE

EDWARD B. HANCE, OF CAMDEN, NEW JERSEY

IRONING-BOARD TABLE

Application filed May 7, 1927. Serial No. 189,498.

The object of my invention is to provide an improved structure that is adapted for use alternately, either as an ordinary table or as an ironing board table, and which is 5 readily convertible to adapt it to one use or the other.

A preferred embodiment of the invention is shown in the accompanying drawings, in which:—

10 Fig. 1 is a plan view of the structure with the ironing board positioned for use.

Fig. 2 is a front view of same.

Fig. 3 is a section on the line 3—3 of Fig. 2.

15 Fig. 4 is a longitudinal sectional view of the structure when converted to an ordinary table.

Fig. 5 is an end view of Fig. 4.

Fig. 6 is a cross-sectional view, looking in the same direction as Fig. 5.

20 Fig. 7 is a view, similar to Fig. 6, with the table top removed and the ironing board raised.

a, b, c, and d are the four corner posts of the supporting frame. Posts a and c are 25 provided with inwardly extending pins e, e. A cross bar f is provided with slots g, each having one long upright arm and one short upright arm. The slotted bar may be positioned as shown in Fig. 6, wherein the pins 30 e engage the upper ends of the long vertical arm of the slots g, or may be positioned as shown in Figs. 3 and 7, wherein the pins e engage the upper ends of the short vertical arms of the slots g. Posts b and d are provided with similar pins e and a similar slotted cross bar f is similarly suspended between the posts.

The cross bars f constitute supports for a 40 jointed ironing board h, i, which, when not in use, may be lowered into the position shown in Fig. 6 and which, preparatory to use, is raised to the position shown in Fig. 7.

45 Section h of the ironing board is provided with depending end ears k, which are slidable on guides m on the cross bars f. A stop n limits the inward movement of ears k and the ironing board. The board occupies this inward position when lowered and not in use, as in Fig. 6, and when raised, as shown in Fig. 7, preparatory to being positioned for

use, or, after use, preparatory to being lowered. The ironing board is slid forward into the position shown in Fig. 3 to position it for use, after which hinged section i of the ironing board is swung out into the position shown in Figs. 1 and 2. A strut j, hinged to section i is then suspended from hook y and is braced against the drawer frame x of the supporting frame, thus firmly supporting the overhanging section i of the ironing board. The movement of the ironing board from the position shown in Fig. 7 to that shown in Fig. 3 so positions the ironing board as to enable the operator to stand close to the edge of the board.

The removable table top o, (which may be of sheet metal) has end cross pieces p, which are provided with longitudinally extending slots s that engaged fixed pins r on posts a and b. Thereby the table top may be moved from a pendant position alongside the supporting frame, as shown in Figs. 1, 2, 3 and 7, to a horizontal position over the supporting frame, as shown in Figs. 4 and 5. In the latter position the table top may be retained in place by means of removable pins t extending through slots s into the posts c and d.

Assume that, as shown in Figs. 4, 5 and 6, the ironing board has been folded, moved in and lowered, and that the table top is in position over the supporting frame. In this position of the parts, the structure is adapted for the ordinary uses for which a table is intended. If it be desired to use the ironing board, pins t are removed and the table is slid laterally and swung down into the position shown in Figs. 1, 2, 3 and 7, in which position the table top hangs suspended by reason of the engagement of pins r in the ends of slots s.

The ironing board is then moved from the position shown in Fig. 6 to that shown in Fig. 7, this movement being effected by an upward movement of cross bars f to bring pins e into alignment with the horizontal parts of slots g, followed by a longitudinal movement of the cross bars f (laterally with relation to the supporting frame) to bring pins e into alignment with the short vertical parts of slots g, the cross bars f being then al-

lowed to drop slightly to cause the pins *g* to rest in the upper ends of the short vertical arms of the slots *g*, as shown in Fig. 6. The ironing board is then moved laterally, on the guides *m* into the position shown in Fig. 3. The section *i* of the ironing board, which is hinged to one end of section *h*, is then swung through an arc of 180° into the position shown in Figs. 1 and 2 and the strut *j* is then moved into supporting position.

10 The structure is now adapted for use in ironing. It will be observed, by reference particularly to Fig. 3, that a space is afforded, back of the rear longitudinal edge of the ironing board section *h*, for fabric being ironed to descend. The depending reach of fabric, however lengthy, will not drop onto the floor, but will be arrested and rest on the drawer frame *x*.

20 When ironing is discontinued, strut *j* is unhooked, section *i* is swung up and down over section *h*, the ironing board *h*, *i* is moved in from the position shown in Fig. 3 to that shown in Fig. 7, the ironing board is lowered 25 into the position shown in Fig. 6 and the table top *o*, *p* is swung up into the operative position shown in Figs. 4, 5 and 6; the structure being thus again converted into a table.

Having now fully described my invention, 30 what I claim and desire to protect by Letters Patent is:—

1. In combination, a supporting frame, an ironing board, supporting members for the ironing board, said supporting members having slots therein, each slot having a horizontal portion and vertical portions extending upwardly from the horizontal portion to different levels, and pins carried by the supporting frame and engaging within said 35 slots, whereby the ironing board may be supported at different levels by selective engagement of the pins with the upper ends of the several vertical portions of the slots.

2. In combination, a supporting frame, an ironing board, supporting members for the ironing board on which the board is slideable 45 forwardly and rearwardly, said supporting members having slots therein, each slot having a horizontal portion and vertical portions extending upwardly from the horizontal portion to different levels, and pins carried by the supporting frame and engaging within said slots, the shorter of the vertically extending portions of the slots being 50 to the rear of the longer whereby the ironing board may be supported at different levels by selective engagement of the pins with the upper ends of the several vertical portions of the slots and moved to a forward position 55 when at the higher level.

In testimony of which invention, I have hereunto set my hand, at Philadelphia, Pennsylvania, on this 5th day of May, 1927.
